(57) **CLAIM**

We claim the ornamental design for a covered casserole, as shown and described.

DESCRIPTION

FIG. 1 is a perspective view of a covered casserole according to the new design;

FIG. 2 is a front view of the covered casserole shown in FIG. 1, the rear view being identical thereto;

FIG. 3 is a side elevation view of the covered casserole shown in FIG. 1, the other side elevation views being identical thereto;

FIG. 4 is a top view of the covered casserole shown in FIG. 1;

FIG. 5 is a bottom view of the covered casserole shown in FIG. 1;

FIG. 6 is a perspective view of another embodiment of a covered casserole according to the new design;

FIG. 7 is a front view of the covered casserole shown in FIG. 6, the rear view being identical thereto;

FIG. 8 is a side elevation view of the covered casserole shown in FIG. 6, the other side elevation views being identical thereto;

FIG. 9 is a top view of the covered casserole shown in FIG. 6, and,

FIG. 10 is a bottom view of the covered casserole shown in FIG. 6.

The broken lines in the drawings are for illustrative purposes only and form no part of the claimed design.
